UNITED STATES PATENT OFFICE

CASPER L. REDFIELD, OF CHICAGO, ILLINOIS

HAIR CLIPPER

Application filed June 9, 1930. Serial No. 459,882.

In ordinary animal shears, the upper blade is driven by an arm which swings in a fixed plane, and the upper blade rests on the face of a lower blade, which face is a plane substantially parallel with the plane in which the arm swings. Under such conditions, it is a comparatively simple matter to keep the two blades in proper contact with each other.

In hair clippers for the use of barbers, it is desirable to have the blades set at an angle of about forty-five degrees, more or less, to the plane in which the driving arm swings. In a case of this kind, the face of the lower blade forms one side of a polygon, and the driving arm acts to move the upper blade in the arc of a circle. To make the upper blade move in a straight line when its driver acts to move it in a curve, it is customary to insert some kind of a spring in the connection between the driving arm and the upper blade. Such spring is flexed to a greater or less extent at each stroke of the blade, and such flexing consumes power. It also acts to lift one end of the upper blade and depress the other alternately, and such action operates to produce non-uniform pressure between the blades. The main purpose of the present invention is to produce an improved form of connection between the driving arm and the upper blade, when the plane of the blade movement is at a considerable angle to the plane in which the driving arm moves.

In the accompanying drawings

Fig. 1 is a plan with the case in section; Fig. 2 is an elevation with the case in section;

Fig. 3 is a section on line 3—3 of Fig. 2;

Fig. 4 is a view in the direction 4 of Fig. 2;

Fig. 5 is a partial section on line 5—5 of Fig. 2; and

Figs 6 and 7 are exaggerated diagrams to show the mode of operation.

At the rear of the device is a head 10 having a projection 11 in the form of a channel. A screw 12 serves to hold a metal bar 13 in a fixed position in the channel of the projection 11, and at the same time furnishes a pivot for another metal bar 14. Preferably, the bar 13 is somewhat stiffer than the bar 14. A

screw 15 acts as an adjustable means for pressing the bars apart.

At a point a little to the left of the screw 15, the bars are bent outward from each other and then back to positions substantially parallel with each other. At points 16, the bars are bent toward each other, and then to substantial parallelism. In the rectangular space thus formed, is a magnetic core 18 and coil 19 supported on bar 13 and acting upon bar 14 as an armature.

When an electric current flows thru the magnet, the bars are attracted toward each other, and when such a current ceases to flow, the bars move from each other by their own resiliency. Because the bar 13 is relatively stiff and carries a considerable load, it moves a less distance than does the bar 14. The device is conveniently operated by an alternating current, and in such operation all movement is confined to the bars 13 and 14. That is, none of the movement is conveyed to the case 32 which is held in the hand while the device is being operated.

On the left end of the bar 13 is secured a bracket 20, in the form of a section of a T-iron, and on the feet of this bracket is an ordinary lower blade 21 secured in the ordinary manner by screws 22. The face of this blade is at an angle of about forty-five degrees to the plane in which the bars 13 and 14 move when attracted by the magnet.

On the left end of the bar 14 is another bracket 23 having wings 24, and on the lower face of this bracket is a narrow rib 25 which lies transversely to the spread of the wings 24. Secured in the wings 24 are pins 26 which enter corresponding holes in the upper blade 27. When the bar 14 is reciprocated, the pins 26 serve to drive the upper blade on the face of the lower blade.

Secured at a suitable place on bar 13 is a spring 28, and similarly secured to bar 14 is a spring 29. These springs overlap each other, as shown in Fig. 3, and a screw 30, threaded into spring 28 and acting on spring 29, serves to apply tension to press the bar 14 downward on its pivot 12. This tension operates thru bracket 23 and rib 25 to press

the upper blade 27 against the lower blade 21.

Fig. 6 is a diagram in which the movable blade 27 is represented in mid-position, and Fig. 7 shows the same parts at one extreme of movement. The lever or arm 14 of Figs. 6 and 7 represents the bar 14 of Fig. 1, and the pivoting point 15 of the diagram corresponds to a point above the screw 15, of Fig. 1. The face of the rib 25 is the arc of a circle drawn from 15 (Fig. 6) as a center, and the upper face of the blade 27 is tangent to this arc. In other words, there is a rolling contact between the bracket 23 and the blade 27, and pressure for this contact is maintained by the springs 28 and 29.

In blades of the kind in common use with barbers, the pitch of the teeth, the distance from one tooth to the next adjacent tooth, is commonly about one-sixteenth of an inch. If the upper blade moves this distance each side of the center line, it is ample for ordinary purposes. In this device, when the upper blade moves in one direction, the lower blade moves in the opposite direction, but as the aggregate of both movements from extreme to extreme does not need to be more than one-eighth of an inch, we can proceed on the assumption that the movement is all in the upper blade.

The distance from the rolling contact on the upper blade to the screw 15 would commonly be in the neighborhood of six inches, and the width of the face of the rib 25 may be less than one-fourth of an inch. While this face is the arc of a circle, that arc is so short that it does not differ sensibly from a straight line.

In the exaggerated drawing of Fig. 7, there is shown an open space A between the face of the movable blade and the arc where it terminates in a shoulder. The proportions of short arc and long radius in the actual structure are such that this space is always less than the diameter of a hair which will be cut by the device. The object of this is to prevent any scrap of hair getting between the roller 25 and the face of the blade 27.

The roller 25 becomes the rib 25 by cutting into the roller to produce shoulders 31 (Fig. 7) beyond which the bracket 23 becomes the wings 24 carrying pins 26. The notch thus produced may have a depth of about one one-hundredth of an inch, but I make it about twice that amount. The reason for this is to avoid crushing any scrap of hair which might fall into this space while the bracket 23 rolls on the upper face of blade 27. It will thus be seen that the open spaces under the rib 25 are always so small that a piece of hair cannot enter, and the spaces under the wings 24 are always so large that a piece of hair will not be caught and crushed.

The pins 26 are in the nature of teeth to a gear which has its center above the screw

15, and in a line perpendicular to the face of the blade 27. The holes into which these pins project correspond to the spaces between two gear teeth on a rack represented by the blade 27, and the proportions are such that both teeth of the gear are always in mesh with the rack.

Secured to the head 10 is a cylindrical case 32 which surrounds the magnet and arms or bars supported by said head. The other end of the case 32 is closed by a head 33 which has an opening for the passage of the arms 13 and 14.

What I claim is:

1. In a hair clipper, a lower blade furnishing an upper plane surface, an upper blade mounted upon said surface, a driving arm moving in a plane at a considerable angle to the plane of the lower blade and having wings extending over the upper blade, driving connections carried by the wings and engaging the upper blade to drive it, and a contact rib carried by the arm and engaging the upper blade between the driving connections.

2. In a hair clipper, the combination with a movable blade and a vibrating arm, of a connection secured to said arm, said connection having wings provided with pins which enter corresponding holes in the blade, and said connection having a blade contacting rib between said pins.

3. In a hair clipper, the combination with a movable blade and a vibratory arm, of a connection secured to said arm, said connection having a centrally disposed rib engaging the upper face of said blade and having laterally disposed wings raised a material distance above the upper face of said blade, and pins secured in said wings and entering corresponding holes in said blade.

4. A pair of cutting blades, a support for the lower blade, a segment of a gear having two teeth engaging openings in the upper blade to drive it, said gear having an arc between the teeth corresponding to the pitch line of the gear and said arc engaging the surface of the upper blade between the openings therein, means for operating the gear to reciprocate the blade, and tension means operating thru the arc of the gear to press the upper blade against the lower blade.
